UNITED STATES PATENT OFFICE.

MARTIN HANSON, OF ST. PAUL, MINNESOTA.

AUTOMATIC DRAIN VALVE.

Application filed May 1, 1922. Serial No. 557,735.

To all whom it may concern:

Be it known, that I, MARTIN HANSON, a citizen of the United States, residing at St. Paul, in the county of Ramsey and State of Minnesota, have invented a new and useful Automatic Drain Valve, of which the following is a specification.

My invention relates to automatic outlet valves for water containers in danger of freezing and the object is to prevent damage to the container by the expansion of the freezing water.

The device is applicable to the water jackets of explosive engines and to any other water vessel or container liable to be exposed to frost.

In the accompanying drawing:

Fig. 1 is a vertical section through a portion of a water container and my device applied thereto.

Fig. 2 is an enlarged section on line 2—2 in Fig. 1.

Fig. 3 is a vertical section of a portion of an explosive engine cylinder and its water jacket, the latter provided with my device.

Referring to the drawing by reference numerals, 5 designates the water holding vessel or container, which may be either open or closed at the top. In the bottom 6 of it is threaded at 7 a vertical tubular body 8 having an internal circular recess 9.

Slidable in said body is a sleeve 10 having near its middle radial apertures 11 through which project into the recess 9 the catches 12 formed at the ends of the legs of a resilient arched spider 13.

14 is a screw to limit the downward movement of sleeve 10 when a foot valve 15 suspended from sleeve 10 by a suitable hanger 40 16 is suitably lowered as shown in dotted lines 15 in Fig. 1.

Slidable in the upper portion of sleeve 10 is an actuator tube 17 whose middle portion is tapering and provided with one or 45 more water ports 18. Above said port the reduced portion of the tube has inserted in it a plug 19 preferably made of hard rubber, and in the plug is secured a standing bolt 20 upon the upper end of which is 50 secured by a nut 21 a soft rubber valve 22 which fits water tight in a valve seat 23 in the upper end of tube 8.

In operative position the valve 22 is normally closed to retain the water and valve 55 15 normally closed to keep cold air out

of the tube 8. When the water 24 commences to freeze and is thereby expanded, it presses the valve 22 down, as in the dotted lines 22 in Fig. 1, thereby causing the actuator tube 17 to press the spider legs inward and thus disengage the catches 12 from recess 9 and letting sleeve 10 drop down on screw 14 and opening valve 15. The water is now free to run out and leave the container empty enough so it cannot be damaged by freezing of any water left in it. When the danger of frost is past the valve or plate 15 is simply pushed upward to closed position. This will also close valve 22, and the water container may be refilled. 70 It is understood that the outward spreading tension of the spider is sufficient to support the actuator tube and valve 22 as long as the latter carries only the pressure of the water upon it, but it yields to the extra 75 pressure caused by freezing of the water. In Fig. 3 25 designates a portion of an engine cylinder having the water jacket 5 for cooling the cylinder.

What I claim is:

1. The combination with the lower part of a water container of a vertically disposed water outlet tube depending therefrom and having in its upper end a valve seat and a vertically movable valve therein, and an 80 internal circular recess farther down in the tube, a sleeve slidable in the tube and having radial apertures, a resilient arched spider in the sleeve with its legs normally projecting through the apertures and into the circular recess, a laterally perforated actuator tube suspended from the valve and having its lower end supported on the legs of the spider so as to press them together and thereby disengage them from the circular recess when the top of the valve is subjected to a predetermined degree of pressure. 90

2. The structure specified in claim 1, and means limiting the downward movement of said sleeve. 100

3. The structure specified in claim 1, and a second valve suspended from the sleeve and arranged to close the lower end of the outlet tube when the first mentioned valve closes the upper end of it. 105

4. The structure specified in claim 3, and means for automatically supporting both valves when they are open.

In testimony whereof I affix my signature.
MARTIN HANSON.
